UNITED STATES PATENT OFFICE.

CARL A. GUSTAFSON, OF MINNEAPOLIS, MINNESOTA, ASSIGNOR TO RUSSELL GRADER MANUFACTURING COMPANY, OF MINNEAPOLIS, MINNESOTA, A CORPORATION OF MINNESOTA.

CRUSHING AND SCREENING APPARATUS.

Application filed July 9, 1924. Serial No. 724,998.

This invention relates to new and useful improvements in crushing and screening apparatus particularly adapted for use in the construction of public highways, roads, etc. 5 to prepare to a substantially uniform size material such as gravel used in the construction thereof, and more particularly relates to such apparatus of the portable type which may readily be moved from place to place.

In the building of public highways and roads it has been found desirable that the rough material such as gravel, used in the construction thereof, be of a substantially 15 uniform size in order that best results may be obtained. It is therefore desirable that means be provided whereby the gravel, as it is taken from the pit, may be passed through a sizing device wherein the coarser 20 material such as stones, will be crushed to a certain degree of fineness before being discharged into the hopper or other suitable receiving means for subsequent use in the construction of the road.

25 It is therefore the object of this invention to provide an improved screening and crushing apparatus adapted for use to prepare to a substantially uniform size, the usual rough material used in the construction of 30 roads and the like.

A further and more specific object of the invention is to provide such an apparatus which is self-contained and is portable so that it may readily be moved about from 35 place to place.

Other objects of the invention will more 40 fully appear from the following description and the accompanying drawings and will be pointed out in the annexed claims.

45 In the drawings there has been disclosed a structure designed to carry out the various objects of the invention but it is to be understood that the invention is not confined to the exact features shown as various changes may be made within the scope of the claims which follow.

In the accompanying drawings forming a part of this specification,

50 Figure 1 is a longitudinal sectional elevation on line 1-1 of Figure 2 of my improved screening and crushing apparatus, showing how the coarser material is discharged from the shaking screens into a crusher to be broken up;

Figure 2 is a cross-sectional view on the 55 line 2-2 of Figure 1 showing how the material is received from the crusher and discharged into a bucket conveyor to be returned to the shaking screens or grizzly for final discharging into the receiving hopper; 60

Figure 3 is a similar cross-sectional view on the line 3-3 of Figure 1 showing how the crushed material is discharged onto the lower coarser screen of the grizzly;

Figure 4 is a detail plan view of the receiving end of the grizzly; and

Figure 5 is a sectional elevation of the receiving end of the grizzly showing a modified construction.

The novel screening and crushing plant 70 features in this invention and shown in the accompanying drawings comprises a hopper 6 rigidly mounted in the frame of the structure. The main frame preferably consists of opposed side beams 7 connected together at their ends by means of cross-members 8 thereby forming a rectangular frame which is suitably mounted upon the front and rear axles 9 and 11 carried by the usual wheels 12 and 13. The hopper 6 is arranged 75 between and is secured to the side beams 7, (Figure 3).

An oscillating screen or grizzly is mounted above the hopper 6. This grizzly preferably comprises a frame 14 suspended from 85 cross-bars 15 by means of links 16 as particularly shown in Figures 1 and 3. The form of grizzly here shown preferably comprises an upper screen 17 of comparatively fine mesh and a lower screen 18 of a 90 relatively coarser mesh. A cross shaft 19 is mounted in the frame of the structure beneath the discharge end of the grizzly and this shaft has mounted thereon a pair of eccentrics 21, on which are arranged the pitmen 22, having their opposite ends pivotally connected to the frame 14 of the grizzly. Thus, when the shaft 19 is rotated an oscillating or shaking movement will be 95 imparted to the grizzly thereby causing the finer material to pass therethrough into the hopper 6 and the coarser material to be discharged therefrom into a suitable crusher 100 mounted adjacent the rear end of the apparatus. This crusher is of usual construction and comprises a frame 23 in which is mounted the stationary jaw 24 adapted to

105 cooperate with the movable jaw 25 to crush

the coarser material as it is discharged thereinto. The movable jaw 25 is operated by means of an eccentric 26 mounted upon the shaft 27 of the crusher. A suitable fly-wheel or pulley 28 is mounted on the shaft 27 adapted to receive a belt 29 by means of which the entire apparatus may be driven from a suitable source of power.

The jaws 24 and 25 extend crosswise of the frame, the stationary jaw being next to the hopper and below the discharge end of the screens (Figure 1). A plate 25 is arranged above the stationary jaw and serves to direct material passing over the screens into the space between the jaws of the crusher.

The material such as gravel, may be delivered to the grizzly by any suitable means, as by the conveyor belt 31 operated by a roller 32 upon a suitable conveyor frame 33. This conveyor is preferably of considerable length so as to extend into the pit from which the material is being removed and delivered to the grizzly. I claim no invention in the construction of this conveyor and I have therefore shown only a portion thereof.

A hood 34, having a cover 35 substantially closing the rear end thereof, is mounted at the discharge end of the grizzly and over the jaws of the crusher. This hood functions to prevent particles of the material such as pieces of stone from flying out of the crusher while the machine is in operation, which might cause injury to workmen laboring about the apparatus. An operator's platform 36 is also mounted adjacent the discharge end of the grizzly and a portion of this platform forms the upper wall of the hood 34, as shown in Figures 1 and 2. A perforated plate 37 is mounted in that portion of the platform comprising the upper wall of the hood 34, and the perforations in this plate are of such size that the operator may watch the action of the crusher during the operation of the machine.

As the coarser material, discharged into the crusher from the upper screen 17 of the grizzly, is crushed by passing between the jaws 24 and 25 of the crusher, it is discharged into an oscillating, inclined spout or trough 38. This trough conveys the crushed material into the lower or receiving end of a bucket conveyor 39 mounted adjacent one side of the machine, as particularly shown in Figure 2. This conveyor is preferably mounted at an incline and the upper end thereof extends to a point above the hopper 6. An inclined receiving spout 41 is mounted at the upper end of the bucket conveyor in position to receive the material as it is discharged therefrom, and to convey it back to the grizzly. The frame 42 of the bucket conveyor and also the spout 41 are preferably supported by means of a structural frame comprising the upright posts 43 and 44 and the horizontal cross-members 45 and 46

which are suitably riveted together and mounted upon and secured to the side-beam 7 of the main frame. The upper end of the bucket conveyor is supported upon a sprocket wheel 47 carried by a shaft 48 upon one end of which a sprocket wheel 49 is mounted. A drive chain or belt 51 is mounted upon the sprocket wheel 49 and on a relatively smaller sprocket 52 mounted upon one end of the cross-shaft 19, so that the conveyor 39 will be operated simultaneously with the grizzly and crusher when the entire apparatus is in operation. A suitable drive sprocket 53 is mounted upon the opposite end of the cross-shaft 19 and this sprocket is driven from the crusher shaft 27 by means of a chain belt 54 shown in dotted lines in Figure 1.

As shown in Figure 2, the oscillating trough 38 mounted beneath the crusher, is preferably supported upon oscillating links 55, each having one end pivotally mounted on the main frame of the apparatus. This trough is actuated by means of a pitman 56 having one end pivotally connected thereto and its other end mounted upon an eccentric 57 secured to a shaft 58 which is mounted in suitable bearings 59, preferably in parallel relation to the side beams 7, 7, of the main frame of the apparatus. The shaft 58 is rotated by means of a bevel gear drive 61 which is driven from the crusher shaft 27 by means of a suitable chain belt 62, shown in dotted lines in Figure 1.

Referring to the drawings, especially Figures 3 and 4, it will be noted that the coarser material after having passed through the crusher is returned to the grizzly by means of the bucket conveyor, but is not discharged onto the upper screen 17, but through an opening 63 provided therein and directly into the lower coarser screen 18. The crushed material will then pass through the screen 18 and into the hopper 6, but should some of the material still be too coarse to pass through the lower screen it will again be conveyed to the crusher for subsequent crushing or breaking up until it reaches a degree of fineness which will permit it to pass through the lower screen into the hopper 6. Thus, all of the material delivered into the grizzly from the conveyor 31 must pass through the screens but it is discharged into the main hopper 6.

Means are also provided for conveying the material from the hopper 6 and delivering it to a suitable receiving means such as a truck, wagon or bin. Such means preferably consists in the provision of a delivery conveyor pivotally mounted upon brackets 64 secured to the main frame of the structure and having its receiving end extending beneath the hopper 6 and its other end outwardly extending therefrom as shown in Figure 3. The frame 65 of this conveyor is adjustably supported adjacent its outer

end by means of cables or chains 66, each having one end secured to the upright posts 43 of the frame and passing around sheaves 67 and back and around a shaft 68 so that when the shaft 68 is rotated, the outer end of the conveyor may be raised or lowered, as desired. The shaft 68 is manually operable by means of a hand wheel 69 and is locked in position by means of a ratchet device 70, of ordinary construction, as shown in Figure 2. The sheaves 67 are connected to the conveyor frame by means of rods 71. Rollers 72 and 73 are mounted adjacent each end of the conveyor frame 65 and a conveyor belt 74 is mounted on these rollers and is supported therebetween by means of a series of spools 75 and rollers 76, rotatably mounted on the frame 65. The lower reduced portion 77 of the hopper 6 is open and is preferably inclined to substantially conform to the angle of the belt as shown in Figure 3. Thus it will be noted that the belt 74 forms the bottom of the hopper 6 and when this belt is inoperative the hopper 25 may be filled without danger of the material running out of the bottom of the hopper and onto the ground. This is effected by means of the surface of the belt resting on the concaved spools 75, as shown in Figure 30 2. A gear wheel 78 is mounted on the shaft of the upper roller 73 of the conveyor and this gear meshes with a pinion 79 secured to a counter-shaft 81 which is mounted in suitable bearings secured to the frame of the conveyor. A pulley 82 is also secured to this shaft and a belt 83 is mounted on this pulley and passes around a clutch pulley 84 mounted on the driven shaft 58. This pulley is provided with a suitable clutch 85 of ordinary construction indicated by dotted lines in Figure 1. This clutch is operable by means of a vertical shaft 86 which has a lever 87 mounted upon the upper end thereof within convenient reach of an operator standing upon the platform 36, shown in full lines in Figure 2 and dotted lines in Figure 1. An auxiliary lever 88 is secured to the lower end of the shaft 86 so that the clutch 85 may also be actuated by an operator standing upon the ground, if so desired. Thus it will be seen that the operation of the delivery conveyor belt 74 may be controlled by means of the clutch 85 actuated by either of the levers 87 or 88. Means are also provided for controlling the operation of the feeding conveyor 31, during the operation of the apparatus. Similarly, to the delivery conveyor this conveyor is also provided with a gear wheel 89 meshing with a pinion 91 mounted on a shaft 92. A clutch pulley 93 is mounted on one end of this shaft and is driven by means of a belt 94 from a pulley 95 mounted on the cross-shaft 19 as shown in Figure 2. The pulley 93 is also provided with a clutch 96, (Figures 2 and 3), of ordinary construction, which is actuated by means of a hand lever 97 arranged adjacent the hand-wheel 69 and lever 87, and also by means of a depending lever 98 whereby it also may be actuated by an operator standing on the ground. Thus, the operation of the feeding and delivery conveyors may be controlled independently of each other and also independently of the operation of the rest of the apparatus. A beam 99 is preferably mounted upon the horizontal angle bars 45 and 46 of the upper portion of the main frame in order to provide means for raising and lowering the feed conveyor 31, as when moving from place to place. When it is desired to move this novel screening and crushing apparatus, it is necessary to disconnect the feed conveyor therefrom. This may therefore be conveniently accomplished by securing an ordinary block and tackle (not shown) to the upper end of the conveyor and to the loop 101 provided at the end of the beam 99, it being understood of course, that the conveyor is detachably connected to the main frame.

Operation.

In the operation of this novel screening and crushing apparatus the material is delivered to the feed conveyor 31 by suitable means such as a drag line bucket, bucket scraper or truck, and the material is then elevated thereon and discharged into the grizzly through which all the smaller material is directly passed into the main hopper 6. The coarser or over-sized material which cannot pass through the upper screen 17 will be conveyed thereon to the crusher at the rear end of the machine. As it is passed through the crusher it will be crushed or broken and discharged therefrom into the inclined oscillating trough 38 from whence it will be discharged into the bucket conveyor 39 and elevated to the spout 41 and returned to the grizzly. The crushed material thus discharged into the grizzly will pass through the opening 63 provided in the upper screen and will be thus discharged directly onto the lower coarser screen 18 through which it will pass into the hopper 6. Should any of the material after having passed through the crusher, still be too large to pass through the screen 18 it will again be returned to the crusher from whence it will be brought again onto the lower screen 18 and this operation repeated until all the material has been reduced to such size that it will pass therethrough into the hopper. It will therefore be seen that all of the material must pass through the screens of the grizzly before entering the hopper 6 and will therefore be substantially of a uniform size. The hopper 6 is preferably of such size as to hold a sufficient amount of mate-

rial to fill a truck or wagon so that when such a device is positioned beneath the discharge end of the delivery conveyor belt 74 and the conveyor is started, by the manipulation of either of the hand levers 87 or 88, the material may be delivered into the truck or wagon in a comparatively short period of time. As soon as the truck or wagon has been loaded the operation of the conveyor 10 will be interrupted by means of the clutch 85 and the hopper 6 will then again begin to fill until it is again desired to empty it. Thus the operation of the delivery conveyor belt 74 may readily and conveniently be controlled to empty or convey the material from the hopper to a suitable receiving means during the operation of the entire apparatus.

In the drawing, I have shown the grizzly 29 as comprising an upper and a lower screen but it is to be understood that a single screen or a plurality of screens may be employed if desired and still be within the scope of the invention.

25 In Figure 5 there is shown a modified construction wherein means are provided to prevent too much of the finer material, such as sand, from getting into the hopper. In certain localities or townships the rough material used in the construction of roads and highways must meet with certain specifications. Such specifications often require that the material must contain only a certain percentage of sand and it is therefore desirable that means be provided whereby a portion of the sand may be prevented from entering the hopper. As shown in this figure, the receiving end of the grizzly comprises two screens, the lower screen 102 being of a comparatively fine mesh and the upper screen 103 of a relatively coarser mesh. Both screens are comparatively short extending only to a point beyond the spout 41 of the bucket conveyor 39. A

45 spout 104 is mounted beneath the lower screen 102 and this spout extends partway into the hopper 6, an opening 105 being provided in the wall of the hopper to provide clearance for the spout. The upper screen 103 extends beyond the end of the finer screen 102 so that a gap 106 is provided between the finer screen 102 and the end of the lower main screen 107 which is preferably of the same mesh as the upper screen 103. The screen 107 extends from the screen 103 to the discharge end of the grizzly. In the operation of this device, the material is discharged from the feed conveyor 31 to the upper screen 103 and the finer material such as the sand and other material which can pass through the screen 103 will pass therethrough into the finer screen 102. The sand will then pass through the screen 102 and drop into the spout 104 from whence it will be discharged onto the ground or a

suitable receiving means (not shown) at one end of the machine. The material that is too coarse to pass through the screen 102 will drop through the gap 106 and into the hopper 6. Also the material that is too coarse to pass through the upper screen 103 will be discharged therefrom onto the lower main screen 107, which, as before stated, is preferably of the same mesh, and will be conveyed along on this screen to the discharge end of the grizzly and into the crusher wherein it will be crushed and returned to the upper screen 103 in the manner similar to that described with reference to the prior figures.

The details of the construction may be varied in many particulars without departing from my invention.

I claim as my invention:

1. An apparatus of the class described, comprising, in combination, a frame, a hopper mounted therein, a screening means arranged above said hopper and having a fine and coarse mesh, and means for delivering the material initially to the fine mesh, a crusher mounted at one end of said screening means adapted to receive a portion of the material discharged into said screening means, and means for returning the material passing through said crusher to the coarse mesh portion of said screening means.

2. In the apparatus of the class described, the combination of a hopper, a plurality of oscillating screens of different meshes arranged above said hopper in superposed spaced relation with the finer screen above and the coarser screen below, means for feeding material initially onto the finer screen, a crusher at one end of the screens adapted to receive and crush the over-sized material not passing therethrough, and means for returning to the coarser screen the material passing through said crusher.

3. In an apparatus of the class described, the combination of a hopper, a grizzly mounted for oscillatory movement over said hopper, said grizzly comprising an upper screen of comparatively fine mesh and a lower screen of relatively coarser mesh, means for feeding material onto said upper screen, the finer material passing through said screens and into said hopper, a crusher arranged at one end of said grizzly adapted to receive and crush the over-sized material and means for returning to the lower coarser screen of said grizzly the material passing through said crusher.

4. In an apparatus of the class described, the combination of a frame, a hopper mounted therein, an oscillating grizzly having screening surfaces of varying mesh, means for feeding material into said grizzly, a crusher mounted to receive and crush the over-sized material from said grizzly, a conveyor for returning to a cer-

tain mesh of said grizzly the crushed material from said crusher so that a portion of it may pass through said grizzly and into said hopper.

5 5. An apparatus of the class described, comprising, in combination, a portable frame, a hopper mounted therein, a fine and coarse screening means above said hopper, having a fine screen for removal of sand, 10 and a chute extending from below said fine screen and arranged to discharge fine material outside of said hopper, and a crusher arranged at the opposite end of said screen, adapted to receive the material that passes

15 over the tail of said screening means, the middle portion of said screening means discharging material into said hopper.

6 6. An apparatus of the class described, comprising in combination a frame, a hopper mounted therein, a screening means located above said hopper, and having a head section of fine mesh arranged to deliver the fine material passing through said head section outside of said hopper, a crusher mounted to receive the tailing material that passes over said screening means, the material that passes through said screening means intermediate the head and tail thereof being discharged into said hopper.

7 7. An apparatus of the class described, comprising, in combination, a portable frame, a hopper mounted therein, an oscillating screening means arranged above said hopper and provided with screening surfaces of different mesh, a crusher arranged at one end of said screening means adapted to receive and crush the material that passes over said screening means, means for returning to a screening means surface of certain mesh the material passing through said crusher, and means located in proximity to said crusher for controlling the different instrumentalities of the machine.

8. In an apparatus of the class described,

the combination, with a portable frame, of 45 a hopper mounted therein, a screening means arranged above said hopper, a crusher arranged at the tail end of said screening means and adapted to receive material that passes over said screening means, a guard 50 arranged over said crusher and adapted to deliver the material passing from said screening means into said crusher, said guard being provided with a perforated door permitting examination of the material 55 passing from said screening means to said crusher.

9. An apparatus of the class described comprising a frame, a hopper mounted therein, a screening means mounted for oscillation above said hopper and comprising fine and coarse screening surfaces, and means for initially delivering the material to the surface with fine mesh, a crusher arranged to receive the tailings from said 60 screening means or the coarse material too large to pass therethrough, and means for receiving the crushed material from said crusher and returning it to a coarser mesh surface of said screening means. 70

10. An apparatus of the class described comprising a frame, hopper mounted therein, an oscillating screen arranged over said hopper and whereto a body of the coarse material is delivered, said screen having a 75 comparatively fine and coarse mesh, the fine mesh section of said screen being adapted to deliver fine material passing therethrough outside of said hopper, a crushing means arranged to receive the coarse tailings 80 from said screen which are too large to pass through the meshes thereof, and means arranged to receive such crushed material and elevate it for delivery to said screen for re-separation. 85

In witness whereof, I have hereunto set my hand to this 30th day of June, 1924.

CARL A. GUSTAFSON.
